UNITED STATES PATENT OFFICE.

EDWARD J. DICKSON, OF WENATCHEE, WASHINGTON.

VALVE REAMER AND REFACER.

1,236,408.

Specification of Letters Patent. Patented Aug. 14, 1917.

Application filed July 27, 1916. Serial No. 111,560.

To all whom it may concern:

Be it known that I, EDWARD J. DICKSON, a citizen of the United States, residing at Wenatchee, in the county of Chelan and 5 State of Washington, have invented certain new and useful Improvements in Valve Reamers and Refacers, of which the following is a specification.

This invention relates to new and useful 10 improvements in valve grinding devices and more particularly to a valve reamer and refacer, and the primary object of the invention is to provide a device of this character which will enable the valve seat to be 15 reamed and with a slight operation also permit the valve to be re-faced within the engine.

A further object of the invention resides 20 in providing a device of this character which is so designed and applied to use, whereby to utilize the valve stem as a pivot in the actuation thereof.

Still another object of the invention resides in providing a reamer head or member 25 of substantially inverted cone-shaped design, the wall of which consists of a plurality of ribs, the inner and outer edges of said ribs being constructed to form cutting faces.

30 A still further object resides in providing a device the outer edges of which are designed to ream the valve seat and the inner edges of which are designed to re-face the valve.

35 A still further object of the invention resides in providing a device which is simple and durable in construction, inexpensive to manufacture and one which will be very efficient and useful in operation.

40 With these and other objects in view, my invention consists in the novel features of construction, combination and arrangement of parts as will be hereinafter referred to and more particularly pointed out in the 45 specification and claims.

In the accompanying drawings forming a part of this application:—

Figure 1 is a section through a cylinder head showing a device constructed in accordance with my invention and applied to use;

Fig. 2 is a perspective view of the hand operating portion of the device with a portion of a tool support thereon;

55 Fig. 3 is a similar view of the reaming and re-facing member removed;

Fig. 4 is a side elevation, partly in section, of the operating member removed; and

Fig. 5 is a perspective view of a slightly 60 modified form of the invention.

In describing the invention I shall refer to the drawings in which similar reference characters designate corresponding parts throughout the several views and in which 65 1 designates a cylinder head having a threaded opening 2 therein whereby entrance may be had thereto and the usual plug 3 is provided for closing said opening. Arranged in the head is the valve seat 4 70, against which is adapted to be seated the valve 5, the latter being provided with the depending stem 6. The valve 5 is provided in its upper face with the usual recess or slot 7, although in my improved device I 75 have provided means for operating valves with other recesses therein as will appear later.

My improved reamer and re-facer consists of a substantially inverted cone-shaped head 80 or body member 8, the same comprising an upper annular rim 9, and a lower collar 10, said rim and collar being connected together by means of a plurality of ribs or the like 11. This member 8 is cast or otherwise constructed of metal and the ribs have their outer and inner edges designed to form cutting edges respectively designated as 12 and 13. These ribs 11 may, therefore, be termed cutting or facing tools, and the same are so 90 constructed as to provide the same angle with respect to a vertical plane on both the inner and outer edges.

This member 8 is adapted to rest, when placed in operation, on the valve seat 4, as 95 shown in Fig. 1 of the drawings, and the valve 5 is adapted to rest on the inner edges of the ribs 11 thereof, the stem of said valve being directed through the collar 10 of said member 8. A bushing 14 is loosely arranged 100 in the collar 10 to receive the stem 6 directly therethrough, and bushings with bores of various sizes may be provided according to the diameter of the stem of the valve. The bushing is provided with a head or flange 15 105 at its upper end to rest upon the upper edge of the collar portion 10. The stem of the valve 5 is guided through this bushing and further guided through a bearing or the like 16 formed in the cylinder head just below 110 the valve seat.

At the junction of the rim 9 with the ribs

11 of the member 8, an annular shoulder 17 is provided and formed on the inner periphery of said rim 9 at predetermined points thereon are the inwardly projecting locking lugs or the like 18.

A supporting member 19 is also provided which consists of a collar 20 and a plurality of arcuate depending legs 21 which are formed integral with said collar and provided at their lower ends with the laterally extending feet or the like 22. These feet are adapted to be received on the annular shoulder 17 of the member 8 and the member 19 may be turned so as to permit said feet 22 to be disposed immediately under and in locking position below the lugs 18, as clearly shown in Fig. 1 of the drawings. The collar 20 of the member 19 is internally threaded to receive in engagement therewith the externally threaded bushing 23, the latter extending a short distance below the collar 20.

A stem 24 is adapted to be extended through the bore of the bushing 23 and has removably engaged with its lower end a head 25 which is tapered at its lower edge so as to form a key or the like for entrance into the slot 7 of the valve, as clearly shown in Fig. 1 of the drawings. The stem 24 has a bore therethrough adjacent its upper end and the handle or turning member 26 is provided to extend therethrough whereby the device may be manually operated.

In applying the device to use, the plug 3 is first removed from the cylinder head whereupon the valve 5 is removed from its seat. The member 8 is then positioned on the seat 4 and the valve positioned within the interior of the member 8 so that the stem 6 of said valve projects through the bushing 14 and guided through the bearings 16. The supporting member 19 is then positioned on the member 8 so as to be located below the lugs 18 thereof, it being understood that the stem 24 is applied to said member 19 previously. The member 24 is then positioned so that the head 25 engages with the slot 7 in the valve and the bushing 23 is then turned home so as to permit the lower edge thereof to engage with the head 25 and lock the same against the valve 5. By so locking the head 25 against the valve 5, said valve is also locked tightly against the inner walls of the member 8 and the several parts of the device are thus locked tightly together. The member 26 is then positioned on the stem 24 and the complete device is turned as is usual in connection with the reaming of valves and valve seats. By so turning the device, the cutting faces 12 of the ribs 11 will ream the valve seat 4 effectively. When this has been completed, the bushing 23 is slightly retracted which releases the valve from binding tightly against the faces 13 of the ribs 11 and the

valve is then placed in position with respect to the member 8. The stem 24 is then turned in the usual manner, the operator exerting pressure upon the bushing 23 with his fingers to prevent turning of the member 8 on the valve seat, and the valve proper will be re-faced by contacting with the facing edges 13 of the ribs 11. These ribs being spaced one from the other, as shown, will allow the carbon and other extraneous matter which forms on the valve to readily pass through the member 8 and fall therebelow. In both operations, to wit:—The reaming of the valve seat and the re-facing of the valve, the valve stem 6 is used as a pivot or the like for the complete device and as the facing edges 12 and 13 of the ribs 11 are disposed at the same angle with respect to the vertical plane, the valve seat and the valve will be respectively reamed and re-faced at the proper angle so that the valve will seat properly after the operation is completed. When the reaming and re-facing operations are completed, the device may be removed and the valve replaced in the usual manner.

As stated above, the usual valves are provided with a slot or key way in the upper face thereof with which may be engaged a key or other instrument for operating the valve in the grinding or re-facing process. However, it is a known fact that certain valves are provided with other means for the purpose of accomplishing this end. In Fig. 5 I have shown a slightly modified form of the invention, wherein a valve 27 has its upper face provided with a plurality of orifices 28. In order to operate my improved device in connection with a valve of this character, a disk-like head member 29 is provided which may be quickly and readily attached to the lower end of the stem 24, it being understood that the head member 25 in the preferred form is previously attached thereto. This disk-like head member 29 is provided with depending studs 30 or the like which are arranged in engagement with the holes 28. It will be readily seen that when the stem 24 is lowered the studs 30 may be entered into the orifices 28 and the valve operated as hereinabove described. Otherwise, this form of the device is the same as the preferred form above described.

From the above description of the construction of my improved device, the operation thereof will be readily understood and it will be seen that I have provided a simple inexpensive and efficient means for carrying out the objects of the invention.

While I have particularly described the elements best adapted to perform the functions set forth it is obvious that various changes in the form, proportion and in the minor details of construction may be resorted to, within the scope of the appended

claims without departing from the spirit or sacrificing any of the principles of the invention.

Having thus described my invention, 5 what I claim and desire to secure by Letters Patent, is:—

1. A device of the character described consisting of a hollow inverted cone-shaped reaming head adapted to be arranged in a 10 valve seat and to receive a valve therein, said head having a bearing formed at its apex adapted to receive the valve stem of said valve, and having its inner and outer walls constructed to form and provide facing 15 edges, means for actuating the valve with respect to said head to re-face the valve, and additional means in connection with said valve actuating means whereby to lock the valve to the head and to actuate 20 the head to ream the valve seat.

2. A device of the character described consisting of a hollow substantially cone-shaped reaming head adapted to be arranged in a valve seat and to receive a valve there- 25 in, said head having a vertical bearing at its apex adapted to receive the valve stem of said valve and also having its inner and outer walls constructed to form and provide facing edges, said head being adapted to 30 receive said valve to direct the stem thereof through said bearing so as to utilize the stem as a pivot for said head, an operating member for engaging the valve head to operate the latter with respect to the ream- 35 ing head to re-face said valve, and means for locking said operating member, the valve head and the reaming head together whereby to actuate the head to ream the valve seat.

3. A device of the character described con- 40 sisting of a reaming head of hollow substan- tially cone-shaped design adapted to be ar- ranged in a valve seat and to receive a valve 45 therein, said head having a vertical bearing at its apex, the inner and outer walls of said head being designed and constructed to form 50 facing edges, said head being adapted to re- ceive said valve to direct the stem thereof through the bearing, a bushing loosely 55 mounted in said bearing, a supporting mem- ber removably engaged with the upper end of said reaming head, an operating mem- 60 ber extending through said supporting mem- ber for engagement with the valve head to operate the latter with respect to the inner 65 wall of the reaming head, and means to lock the operating member, the valve and the reaming head together whereby the latter utilizes the valve stem as a pivot when oper- 70 ated to ream the valve seat.

4. A device of the character described con- 75 sisting of a hollow reaming head adapted to be arranged in a valve seat and to receive a valve therein, said head having a bearing 80 at its lower portion adapted to receive the stem of said valve and having its inner and outer walls constructed to provide facing 85 edges, said head being adapted to receive said valve to permit the stem thereof to de- 90 pend through said bearing, means for actu- ating the valve with respect to said head to re-face the valve, and additional means in connection with said actuating means where- 95 by to lock the valve to the head so that the latter may be actuated to ream the valve seat.

In testimony whereof I affix my signature.
EDWARD J. DICKSON.
